UNITED STATES PATENT OFFICE.

CHARLES V. ROTE, OF LANCASTER, PENNSYLVANIA, ASSIGNOR OF ONE-HALF TO RICHARD BLICKENDERFER, OF SAME PLACE.

TRACK-SANDER.

SPECIFICATION forming part of Letters Patent No. 605,558, dated June 14, 1898.

Application filed July 28, 1896. Serial No. 600,767. (No model.)

To all whom it may concern:

Be it known that I, CHARLES V. ROTE, a citizen of the United States, residing at Lancaster, in the county of Lancaster, State of Pennsylvania, have invented certain Improvements in Track-Sanders, of which the following is a specification.

This invention relates to improvements in that class of devices employed for sanding railway-tracks, more particularly the tracks of railways on which electrical cars are used; and the objects of the improvements are, first, to provide more especially for a continuous and uniform feed of damp or wet sand to the rails; second, to regulate the quantity of sand fed to the rails; third, to remove stones and large gravel from the sand as it is fed to the track, and, fourth, to prevent undue noise by the operating parts.

The sanding of the tracks of electric railways is absolutely necessary to the running of cars in cities and towns during wet weather, for the reason that the rails become so covered with slime and mud of the streets that it is impossible for the driving-wheels to take hold of the rails without the aid of sand. This necessity for sanding the tracks is so great that in the larger cities special sanding-cars are run at intervals between the regular traffic cars, and the mechanism for feeding the sand therefrom to the rails has heretofore been so unsatisfactory that with many roads the sand is fed through chutes directly to the rails by hand-shovels. My device feeds sand to the track steadily and uniformly.

My invention is illustrated in the accompanying drawings, forming a part of this specification, and in which—

Figure 1 is a side elevation of a sander embodying my invention and shown attached to a sand-car. Fig. 2 is a top plan view of the frame supporting the sand-box; Fig. 3, a top plan view of the sander; Fig. 4, an elevation of the rear end thereof, and Fig. 5 a longitudinal vertical section of the sand box and chute. Fig. 6 is a vertical section on broken line 6 6 of Fig. 7; Fig. 7, a vertical section on broken line 7 7 of Fig. 6; Figs. 8 and 9, face views of two of the cam-wheels, and Fig. 10 a horizontal section on broken line 10 10 of Fig. 6. Fig. 11 is a perspective view show-

ing the position of the parts when the center brush is engaged with its cam-wheel; Fig. 12, a similar view, but showing the position of the parts when the outer brushes are engaged with their cam-wheels; Fig. 13, a perspective inner face view of one of the bearing-plates of the agitating-shaft; and Fig. 14, a similar view of the rear plate, carrying the stop for the center brush. Fig. 15 is a vertical section of the adjusting mechanism for the vibrating end of the sand-box. Fig. 16 is a transverse section on broken line 16 16 of Fig. 1, showing the connection between the frame and the case inclosing the operating mechanism.

Similar letters indicate like parts throughout the several views.

Referring to the details of the drawings, A indicates the floor of the car, on which the frame supporting the sand-box rests; A', a track-wheel; A², the axle of said wheel, through which the operating mechanism is driven, and A³ the rail.

The frame supporting the sand-box comprises a base having horizontal cheeks B, connected by front and back plates B' B², respectively, and arms B³, extending upward and backward and connected by a cross-bar b. On front plate B' are ears b', through which pass bolts securing the frame to the floor of the car. The bottom of the frame is open; but on cheeks B are inwardly-projecting plates b², on the ends of the parallel edges of which are depending lips b³, through which the case containing the operating mechanism is supported, as will be described, and in plates b² are bolt-holes b⁴, through which pass additional bolts for securing the frame in place. Plates b² are braced by transverse bars b⁵ and brackets b⁶. A transverse rod B⁴ is supported in bearings b⁷ on the upper ends of arms B³.

D indicates an inclined sand-box having in its lower end a delivery-opening d, and on the bottom of said sand-box are downwardly-extending rocking arms D', through eyes d' in the lower ends of which passes the stationary shaft B⁴. Arms D' are located behind the center of the sand-box, the rear end whereof extends back of said rod B⁴, and on the bottom of said sand-box and in front of the cen-

ter thereof are depending ears d^2 , having wrist-pins d^3 on their outer faces, which are engaged by the upper ends of connecting-rods D^2 , to be described.

- 5 Beneath the base of the frame just described is located the case in which is housed the mechanism through which the sand-box is actuated, and there are on the top thereof upwardly-extending lips e , bolted to the lower 10 portions of connecting-plates E , the upper portions of which are in like manner bolted to depending lips b^3 of the frame-base. This case comprises an upper rectangular chamber E' and a lower semicircular chamber E^2 .
 15 The chamber E^2 has vertical flanges e^4 offset from its longitudinal edges and within which the edges of chamber E' rest. On the sides of the longitudinal meeting edges of these chambers are horizontal lugs e^5 , those of 20 chamber E' passing through openings in flanges e^4 and through lugs e^5 . The chambers are secured together by bolts e^6 . In the sides of chamber E' are annular openings e' , having oppositely-located rectangular wings e^2 , and in the back of said chamber E' is an oval 25 opening e^3 . Annular openings e' are engaged by similarly-shaped bosses F , having thereon rectangular wings F' , that engage the corresponding wing-openings e^2 . The bosses F are 30 formed with plates F^2 , that bear against the faces of the sides of the chamber and have wings F^3 , through which they are removably secured to said sides. The wings F' of the bosses F are formed with plates F^2 and their 35 wings F^3 . Through these annular bosses and plates are upright circular-ended slots F^4 , that incline somewhat from the bottom upward toward the front of the chamber, and on the upper rear portions of the faces of said bosses 40 are stops F^5 , having inner uprightly and outwardly inclined faces f . Oval opening e^3 is engaged by a similarly-shaped boss F^6 , and said boss F^6 is formed with a plate F^7 , that bears against the back of chamber E' and has wings 45 f^2 , through which it is removably secured to said back. On the inner face of boss F^6 is a horizontal channeled lip f^3 , in which is adjustably secured an inwardly-extending stop f^4 by means of a set-screw f^5 , working through 50 an opening in said stop and a slot in the bottom of said channel. Slots F^4 form bearings for the spindles g of a revoluble reciprocating rod G , passing through said chamber E' , and to the extremities of these spindles are 55 attached the lower ends of connecting-rods D^2 , the upper ends of which engage pins d^3 of the ears on the bottom of the sand-box, as described. On the center of bar G is fixed a rigid brush G' , which flares outward from its 60 intersection with the rod longitudinally thereof, so that it has a broad outer contact-face g' . On each side of brush G' and adjacent to spindles g are similar brushes G^2 , set approximately at right angles with brush G' , and on the side of said rod opposite to 65 brushes G^2 and also adjacent to spindles g are studs g^2 .

In the end walls of chamber E^2 is journaled a shaft H , having on its outer end a sprocket-wheel I , connected by a sprocket-chain I' with a sprocket-wheel I^2 on axle A^2 of track-wheel A' . On the center of shaft H is a wheel II' , 70 registering with brush G' and having a series of cams formed on and entirely around its periphery. Each of these cams has an inclined face h , a short flattened apex h' , and a shoulder h^2 , the face of which is in a radial plane to the axis of shaft H , the inner edge of each shoulder coinciding with the inner edge of the inclined face h of the succeeding 75 cam. On each side of cam-wheel II' is a similar wheel II^2 , registering with brushes G^2 and having the cams thereon set in a direction opposite to that of the cams on wheel II' . When the car is moving to the rear, center 80 brush G' engages center cam-wheel II' , reciprocating rod G in slots F^4 , the tendency of the cams on said wheel to revolve brush G' backward being overcome by stop f^4 , the extremity of which bears against the rear face of 85 said brush G' . With the reversal of the movement of the car the shoulder adjacent to the cam on which brush G' rests engages said brush and throws it upward and forward, revolving rod G and throwing side brushes G^2 90 into contact with side cam-wheels II^2 , whereby rod G is reciprocated in the same manner as when brush G' engaged cam-wheel II' . Side brushes G^2 are prevented from being 95 swung forward by cam-wheels II^2 by the engagement of studs g^2 on rod G with stops F^5 on bosses F .
 100

The pounding of the brushes as they engage successively with the inclined faces of the cams produces, normally, a rapid and 105 loud succession of reports that are exceedingly objectionable. This I overcome by filling the lower portion of chamber E^2 with thick heavy oil O , known to the trade as "cylinder-stock." I commonly fill the cylinder 110 with this oil up to the journals of shaft H . The oil is caught up by the cam-wheels, and so coats the surfaces of the same as to form a cushion thereon and completely deaden any sound that would otherwise be occasioned by 115 the hammering of the brushes on said wheels. I do not confine myself to the use of cylinder-stock for this purpose, as any other 120 uncouth or sticky matter that will accomplish the same result may be employed.

On the lower end of the sand-box are posts d^3 , having horizontal slots therein, which are engaged by tongues l on the head L of a toothed breaker and sieve acting in conjunction with delivery-opening d in the bottom 125 of the sand-box. In head L is a set of long breaker-teeth L' , that extend diagonally downward across delivery-opening d and have their ends resting on the bottom of the sand-box above said delivery-opening. That part of the shanks l' of breaker-teeth L' adjacent to head L and extending across delivery-opening d are narrow and sharp, with wide spaces between them; but inside of said 130

delivery-opening they are widened out to present broad flat sides l^2 uppermost. From said widened-out portion the teeth taper to the inner ends, which are pointed and have their upper sides beveled, as shown at l^3 .

To the head L or to the parts of teeth L' adjacent thereto are attached the shanks M' of sieve-teeth M . These shanks extend diagonally downward and forward to or near to the front wall of the sand-box, and somewhat above the front end of delivery-opening d shanks M' are connected by curves m with said sieve-teeth, which extend through delivery-opening d back beneath the sand-box and have their ends projecting over the back plate B^2 of the base of the supporting-frame, so as to deliver onto the car-floor behind said frame any matter passing over them. The sieve-teeth M are connected by transverse bars m' and are more numerous than breaker-teeth L' , being so arranged that there shall be a sieve-tooth below each breaker-tooth and one below the center of each space separating said breaker-teeth. The object of this construction is to break up all lumps or masses of sand delivered to the rail and to separate large-sized stones or gravel from the sand.

These sanding-machines are generally used in wet weather, when the tracks are wet and slippery and when the sand itself is moist, heavy, and sticking together in masses, for it is to be remembered that it is not fine sharp sand that is used for this purpose, but the inferior qualities, in which is mixed loam and other earthy matter and impurities. This sand is loaded into the upper end of the sand-box, whence by the vibration thereof, to be described, it works down to the breaker-teeth L' . The finer parts pass between the points of said teeth and down through delivery-opening d into chute D'' , whence it is discharged to the rail. The lumps and masses of sand and gravel, however, are carried over the breaker-teeth until they reach the narrow sharp parts l' thereof, where they are more or less split and broken and fall down onto the sieve-teeth M , which completes the separation of the particles and allows the same to pass down into chute D^3 , the stones and gravel too large to pass between said teeth M being carried back and deposited on the floor of the car, behind the supporting-frame. By having the breaker-teeth widened from the points to the narrow-edged parts l' the lumps are carried to the greatest possible height above sieve-teeth M , so that they may be more completely disintegrated by the greater force with which they strike said sieve-teeth.

To front plate B' of the supporting-frame is secured a plate N' , connected by a neck n with a socket-base N , and to the front of the sand-box is secured a plate P' , connected by a neck p with a cylindrical cap P . In the upper part of base N is a socket n' , and through a threaded opening n^2 in the lower portion of said base passes an adjusting-rod R , having a threaded section r thereon that engages the

thread of said opening. The rod R extends up into cap P and has a head R' secured thereon by a countersunk screw r' , said rod R being actuated through a hand-wheel R^2 on the lower end thereof. The upper end of threaded section r of rod R forms an annular shoulder on which rests a washer W , that plays vertically in socket n' with the up-and-down motion of said rod R , and on said washer rests the lower end of a rubber or other elastic sleeve S , that encircles the stem of rod R and has its upper end bearing against the bottom plate p' of cap P , which it supports. In the chamber P^2 of cap P is a spring S' , coiled around the upper end of rod R and having its lower end resting on bottom plate p' and its upper end bearing against head R' of said rod R .

In Fig. 1 is illustrated a mechanism for temporarily stopping the vibration of the sand-box. On the front of the lower part of cap P is formed a forwardly-projecting lug T , having its end rounded, as shown, and on the front of the top of base N and ranging with lug T are two jaws T' . Between jaws T' is fulcrumed a cam-lever, which comprises a handle V and a cam-ended arm V' . In its normal position the end of handle V rests on the floor of the car, and the cam-arm extends diagonally upward and forward adjacent to the lower side of the nose of lug T . When the car approaches a street-crossing or other place not desirable to sand, handle V is raised, forcing cam-arm V' beneath lug T , thus lifting the front end of the sand-box, as shown by broken lines t , and raising the brush or brushes from the cam-wheels engaged thereby and instantly stopping the vibration of said sand-box. Other means may be employed for accomplishing the same result, but that shown and described is simple and effective.

In operating motion is transmitted from track-wheel axle A^2 through sprocket-wheels I^2 I , and sprocket-chain I' to shaft H , and from said shaft a vertical reciprocating movement is imparted to rod G through the cam-wheels H' or H^2 and brushes G' or G^2 , and this movement of rod G is communicated to the sand-box through connecting-rods D^2 , attached thereto in front of its pivotal connection with stationary shaft B^4 , thus vibrating the sand-box vertically and working any sand therein down to the breaker and sieve-teeth and through delivery-opening d into chute D^3 , whence it is deposited on the rail A^3 . The vertical play of the lower end of the sand-box is regulated by the mechanism located in socket-base N and cylindrical cap P . When this play is to be lessened, the adjusting-rod R is screwed down, thus compressing spring S' and shortening the movement of said cap P , and when the vertical play of the sand-box is to be increased the adjusting-rod R is screwed up, allowing greater length of movement between the ends of spring S' . The elastic sleeve S serves as a cushion to break the shock of impact of the parts. As will be

understood, there is one of these track-sanders on each side of the car, so as to feed to both lines of rails of the track.

I do not restrict myself to the details of 5 construction of the various parts shown and described, as it is obvious that many alterations may be made therein without departing from the spirit and scope of my invention.

My invention involves a radical departure 10 in the construction and principle of operation in sanding-machines and in the mechanism connected therewith, the invention consisting, broadly, in a device for imparting a vertical vibration to the sand-box as the 15 sander is moved either forward or backward in forming a cushion on an actuating part of the mechanism by passing the same through unctuous or other sticky matter and in providing a resilient support for a vibrating end 20 of the sand-box.

Having thus described my invention, what I claim as new, and desire to secure by Letters Patent, is—

1. The combination, in a sander, of a sand- 25 box hinged to a support, a cam-wheel, and a brush connected with the sand-box and at one side of the hinged support, the brush bearing against the cam-wheel and acting, approximately, in line with its connection with 30 the sand-box, for the purpose specified.

2. The combination, in a sander, of a sand- 35 box hinged to a support, a cam-wheel, and a rigid brush connected with the sand-box and at one side of the hinged support, the brush bearing against the cam-wheel and acting, approximately, in line with its connection with 40 the sand-box, for the purpose specified.

3. The combination, in a sander, of a sand- 45 box hinged to a support, a cam-wheel, a brush connected with the sand-box and at one side of said hinged support, the brush being located vertically, approximately, beneath its connection with the sand-box and bearing downward on the cam-wheel, for the purpose 50 specified.

4. The combination, in a sander, of a sand- 55 box hinged to a support, a cam-wheel, a rigid brush connected with the sand-box and at one side of said hinged support, the brush being located vertically, approximately, beneath its connection with the sand-box and bearing downward on the cam-wheel, for the purpose 60 specified.

5. The combination, in a sander, of a sand- 65 box hinged to a support, a cam-wheel, an up-rightly-disposed brush connected with the sand-box and at one side of the hinged support, the brush bearing downward on the cam-wheel, for the purpose specified.

6. The combination, in a sander, of a sand- 70 box hinged to a support, a cam-wheel, an up-rightly-disposed rigid brush connected with the sand-box and at one side of the hinged support, the brush bearing downward on the cam-wheel, for the purpose specified.

7. The combination, in a sander, of a sand- 75 box hinged to a support, a cam-wheel having

the swell thereof terminating in an abrupt shoulder, a brush connected with the sand- 80 box and at one side of said hinged support, 70 the brush bearing downward on the cam-wheel, for the purpose specified.

8. The combination, in a sander, of a sand- 85 box hinged to a support, a cam-wheel having the swell thereof terminating in an abrupt shoulder having the face thereof approxi- 90 mately radial to the axis of said cam-wheel, a brush connected with the sand-box and at one side of the hinged support, the brush bearing downward on the cam-wheel, for the pur- 95 pose specified.

9. The combination, in a sander, of a hinged sand-box, a reciprocating rod, a cam-wheel adapted to impart motion to the reciprocating rod when the sander moves in one direc- 85 tion and a cam-wheel adapted to impart motion to said rod when the sander moves in the opposite direction, and an actuating connection between the reciprocating rod and the sand-box, for the purpose specified. 90

10. The combination, in a sander, of a hinged sand-box, a reciprocating rod, a cam-wheel below the reciprocating rod, a rigid brush on said reciprocating rod and adapted to be engaged by the cam-wheel, and an actuating connection between the reciprocating rod and the sand-box, for the purpose specified. 95

11. The combination, in a sander, of a hinged sand-box, a reciprocating rod, a wheel 100 below the reciprocating rod, provided on its periphery with a cam having a sloping face and a shoulder, a rigid brush on said reciprocating rod and adapted to bear on the periphery of the cam-wheel, and an actuating 105 connection between the reciprocating rod and the sand-box, for the purpose specified.

12. The combination, in a sander, of a hinged sand-box, a revoluble reciprocating rod, wheels below said rod, provided on their 110 peripheries with cams having shoulders and sloping faces, the sloping face and shoulder of the cam of one wheel being set in the direction opposite to those on the other wheel, rigid brushes set at an angle with each other 115 on said rod, one of said brushes being located above each wheel, the brushes being adapted to alternatively engage the peripheries of the cam-wheels beneath them, and an actuating connection between said rod and the sand- 120 box, for the purpose specified.

13. The combination, in a sander, of a hinged sand-box, a case, a revoluble reciprocating rod having its bearing in slots in the ends of the case, wheels below said rod, pro- 125 vided on their peripheries with series of cams having shoulders and sloping faces, the shoulders and sloping faces of the cams of one wheel being set in a direction opposite to those on the other wheel, rigid brushes set at 130 an angle with each other on said rod, one of said brushes being located above each wheel, the brushes being adapted to alternatively engage the peripheries of the cam-wheels be-

neath them, a stud on the rod and adapted to engage a stop on the side of the case when one of the brushes is engaged with a cam-wheel, a stop engaging the other brush when the same engages a cam-wheel, and an actuating connection between said rod and the sand-box, for the purpose specified.

14. The combination, in a sander, of a hinged sand-box, a case, a shaft in the case, a wheel on the center of said shaft, provided on its periphery with a series of cams having shoulders and sloping faces, wheels on said rod and at the sides of the center wheel and having cams similar to those thereon and set in an opposite direction, a revoluble reciprocating rod above the shaft, a rigid brush on the center of the rod and adapted to engage the cams of the center wheel, rigid side brushes set on said rod at an angle with the center brush and adapted to engage the cams on the side wheels, a stop on the rear wall of the case and bearing against the center brush when engaged with its cam-wheel, stops on the ends of the case, studs on said rod and adapted to engage the stops on the end of the case when the end brushes are engaged with their cam-wheels, and an actuating connection between said rod and the sand-box, substantially as and for the purpose specified.

15. The combination, in a sander, of an inclined sand-box having a delivery-opening in the lower end, rocking arms toward the upper end of the sand-box and hinged on a support, wrist-pins on the sand-box between the rocking arms and the delivery-opening, a case below the sand-box, a shaft in the case, a wheel on the center of said shaft, provided on its periphery with a series of cams having shoulders and sloping faces, wheels on said shaft and at the sides of the center wheel and having cams similar to those thereon and set in an opposite direction, a revoluble reciprocating rod having its bearings in vertical slots in the end walls of the case, a rigid brush on the center of the rod and adapted to engage the cams of the center wheel, rigid side brushes on said rod at an angle with the center brush and adapted to engage the cams on the side wheels, a stop on the rear wall of the case and bearing against the center brush when engaged with its cam-wheel, stops on the ends of the case, studs on said rod and adapted to engage the stops on the end of the case when the end brushes are engaged with their cam-wheels, and rods connecting the ends of said revoluble reciprocating rod and said wrist-pins, substantially as and for the purpose specified.

16. The combination, in a sander, of an inclined sand-box having a delivery-opening in the lower end thereof, and teeth raised above the lower end of the delivery-opening and extending back across the same to the bottom of the sand-box and above the delivery-opening, the said teeth being broad and with narrow spaces between them back of said opening, and narrow and with wider spaces be-

tween them over said opening, for the purpose specified.

17. The combination, with a sander, of a sand-box having a delivery-opening, a series of bars extended across said opening, and a second series of bars located below the first series, the bars of the second series being located closer together than those of the first series, for the purpose specified.

18. The combination, in a sander, of an inclined sand-box having a delivery-opening in the lower end thereof, a series of teeth raised above the lower end of the delivery-opening and extending back across the same to the bottom of the sand-box and behind the delivery-opening, and a second series of teeth below the first series and set closer together than those of said first series, said lower series of teeth having their front ends adjacent to the front wall of the sand-box and their rear ends extending behind said delivery-opening, for the purpose specified.

19. The combination, in a sander, of an inclined sand-box having a delivery-opening in the lower end thereof, a series of teeth raised above the lower end of the delivery-opening and extending back across the same to the bottom of the sand-box and behind the delivery-opening, and a second series of teeth below the first series and set closer together than those of said first series, said lower series of teeth having their front ends adjacent to the front wall of the sand-box and their rear ends extending below the bottom of said sand-box behind said delivery-opening, for the purpose specified.

20. The combination, in a sander, of an inclined sand-box having a delivery-opening in the lower end thereof, a chute below the delivery-opening, a series of teeth having their shanks secured in a head, the head being raised above the lower end of the delivery-opening, said teeth extending back over the delivery-opening and having their rear ends resting on the bottom of the sand-box and above said delivery-opening, the teeth being broad and with narrow spaces between them back of said opening, and narrow and with wider spaces between them over said opening, and a second series of teeth below the first and having their front ends adjacent to the front wall of the sand-box and thence extending downward and backward through the opening and with their ends projecting behind said chute, the lower series of teeth being set closer together than the upper, substantially as and for the purpose specified.

21. The combination, in a sander, of a sand-box, a hinged support for the sand-box, a support located on a side of the hinged support, a cushion interposed between said side support and the sand-box, and a device adapted to vibrate the sand-box about the hinge-support.

22. The combination, in a sander, of a sand-box, a hinged support for the sand-box, a resilient support on one side of the hinged sup-

port, and a device adapted to vibrate said sand-box about the hinged support.

23. The combination, in a sander, of a sand-box, a hinged support for the sand-box, a resilient support on one side of the hinged support, means for regulating the play of the resilient support, and a device adapted to vibrate said sand-box about the hinged support.

24. The combination, in a sander, of a sand-box, a hinged support for the sand-box on one side of the center thereof, a resilient support on the other side of said center, and a device connected with the sand-box between said supports and adapted to vibrate said sand-box about the hinged support.

25. The combination, in a sander, of a sand-box, a hinged support for the sand-box, a hollow cap attached to the sand-box on one side of the hinged support, a stationary base below the cap, a threaded adjusting-rod engaging a threaded opening through said base, the stem of said rod extending into the cap, a resilient connection between said stem and the cap, and means for vibrating the sand-box about its hinged support, for the purpose specified.

26. The combination, in a sander, of a sand-box, a hinged support for the sand-box, a hollow cap attached to the sand-box on one side of the hinged support, a stationary base below the cap, a threaded adjusting-rod engaging a threaded opening through said base, the stem of said rod extending into the cap, a resilient connection between said stem and the cap, an elastic sleeve around the stem of said rod and between the cap and base, and means for vibrating the sand-box about its hinged support, for the purpose specified.

27. The combination, in a sander, of a sand-box, a hinged support for the sand-box, a hollow cap attached to the sand-box on one side of the hinged support, a stationary base below the cap, a threaded adjusting-rod engaging a threaded opening through said base, the stem of said rod extending into the cap, a resilient connection between said stem and the cap, an elastic sleeve around the stem of said rod and between the cap and base, and means for vibrating the sand-box about its hinged support, for the purpose specified.

28. The combination, in a sander, of a sand-box, a hinged support for the sand-box, a resilient support for said sand-box, mechanism for vibrating the sand-box about the hinged support, and a device for disconnecting the resilient support and thereby disengaging the vibrating mechanism, for the purpose specified.

29. The combination, in a sander, of a sand-box, a hinged support for the sand-box and adjacent to one end thereof, mechanism for vibrating said sand-box about the hinged support, a cap on the vibrating end of the sand-box and having a lug thereon, a stationary base below the cap and having jaws thereon, a resilient mechanism housed in said cap and base, and a cam-lever fulcrumed between the jaws and adapted to engage said lug and disconnect the resilient mechanism by raising said cap, substantially as and for the purpose specified.

CHARLES V. ROTE.

Witnesses:

C. G. BASSLER,
WM. R. GERHART.

low the cap and having a socket in the top thereof, a threaded adjusting-rod engaging a threaded opening through said base, the upper end of said rod forming a shoulder in the 45 socket in the base, the stem of the adjusting-rod extending into the cap and having a removable head thereon, a washer on said shoulder, an elastic sleeve embracing the stem of the adjusting-rod and having one end bearing on the bottom of the cap and the other end on said washer, a spring coiled around the stem of the rod and having its ends bearing on the head of the said stem and on the bottom of the cap, and means for vibrating 55 the sand-box about its hinged support, substantially as and for the purpose specified.

28. The combination, in a sander, of a sand-box, a hinged support for the sand-box, a resilient support for said sand-box, mechanism 60 for vibrating the sand-box about the hinged support, and a device for disconnecting the resilient support and thereby disengaging the vibrating mechanism, for the purpose specified.

29. The combination, in a sander, of a sand-box, a hinged support for the sand-box and adjacent to one end thereof, mechanism for vibrating said sand-box about the hinged support, a cap on the vibrating end of the sand-box and having a lug thereon, a stationary base below the cap and having jaws thereon, a resilient mechanism housed in said cap and base, and a cam-lever fulcrumed between the jaws and adapted to engage said lug and disconnect the resilient mechanism by raising said cap, substantially as and for the purpose specified.
